ELECTRICALLY PROPELLED WHEEL-CHAIR

Arthur C. Guyton, Oxford, Miss.

Application September 3, 1948, Serial No. 47,723

13 Claims. (Cl. 180—6.62)

1

This invention relates to electrically propelled wheel chairs and it has for its primary purpose to provide a combined propelling and steering mechanism controlled by a single master control switch, which enables the occupant of the chair to direct the movement of the chair completely by slight movements of a lever.

Electrically driven wheel chairs are known but they require, as a rule, the use of a steering lever or other mechanism directing a steering or guiding wheel in addition to the mechanism which determines the backward or forward driving movement of the chair and the stopping and starting of the wheel movement. Moreover most of these mechanisms have to be built into the chair and are not removable or interchangeable.

It is the main purpose of the invention to eliminate the special steering mechanism and to use a single control mechanism for regulating all directional movements and the driving or propelling movement as well as the direction of such propelling movement.

It is a further purpose of the invention to provide a master control switch provided with a single control lever movable in different directions the movement of the said control lever in the desired direction determining the angular as well as the propelling movement and the direction of the latter.

It is a further object of the invention to provide a unit for producing a combined steering and driving of a wheel chair which may be mounted on any standard chair and may be secured thereon by holding or locking means and which is therefore easily removable and replaceable as a whole.

It is a further object of the invention to provide a combined propelling and steering mechanism acting on the main driving wheels of the wheel chair which permits to either drive both wheels or to lock one wheel while driving the other in the desired direction of propulsion, this simultaneous locking and propelling of the two wheels and the resulting difference in speed of the wheels being used for the change of the direction of driving.

It is a further object of the invention to provide means for maintaining frictional engagement between the main driving wheel and a driving roller which is rotated by means of an electromotor, which engagement may be released, temporarily for steering purposes for each wheel separately.

It is a further object of the invention to provide combined frictional driving and braking means adapted to act on each of the main driving wheels

2

of the wheel-chair, which frictional driving means are connected with an electromotor and are maintained in normal frictional engagement with the main driving wheel of the chair, the said engagement being released and the brake being applied separately for each wheel for the purpose of changing the angular direction in which the chair is headed.

It is a further object of the invention to provide 10 separately operable electromagnetic means for lifting the frictional engagement between a driving roller engaging one of the main propulsion wheels of the wheel chair, and for simultaneously applying a braking member, said driving roller being driven by an electromotor the current supply and the direction of flow of which is controlled by a master control switch, said switch simultaneously controlling the said electromagnetic devices, said controlling means being so arranged that simultaneous control of the driving and brake action may be obtained by a single master control lever of the master control switch.

It is a further object of the invention to provide 15 means such as a number of relay switches, changing the direction of current flow through the electromotor driving the frictional driving rollers acting on the main driving wheels of the wheel chair, which relay switches are controlled by the master control switch.

It is a further object of the invention to provide 20 frictional driving means for the main drive wheels of a wheel chair which are driven by the same shaft, rotated by an electromotor in one or the other direction, these driving means being associated with frames carrying braking means, which frames are acted upon by solenoids controlled by a master control switch, which also controls the starting, stopping and the direction of rotation of the electromotor, each of said solenoids by 25 elastic deformation of the driving shaft moving the driving roller of one side out of engagement and the brake member into engagement with the main driving wheel, thus permitting braking of one main driving wheel and driving of the other main driving wheel, upon energization of one of the solenoids, said energization thus producing a change in the heading or angular direction of the wheel-chair.

A further object of the invention consists in 30 providing a further switching means for changing the speed of the electromotor.

Further and more specific objects will be apparent from the following specification.

The invention is illustrated in the accompanying 35 drawings, showing one embodiment thereof

and several modifications of the details used, by way of example. It is to be understood however, that the example shown serves mainly the purpose of explaining the principle of the invention and the best mode of applying said principle, but does not show the sole way of practical application of the invention. Modifications of the example shown, some of which will be described or foreshadowed by the detailed specification or will be obvious to the expert skilled in the art, are therefore not necessarily departures from the invention.

In the drawing:

Figure 1 is an elevational side view of an electrically propelled invalid chair, according to the invention.

Figure 2 is a perspective view of the electric driving mechanism when viewed from the rear of the chair.

Figure 3 is a sectional plan view of the chair, the section being taken along line 3-3 of Figure 1.

Figure 4 is an elevational side view of the control switch unit mounted on the chair which contains all the means necessary for propelling at different speed, and for selecting the direction in which the chair is intended to move.

Figure 5 is an elevational sectional view of the same switching unit the section being taken along line 5-5 of Figure 4.

Figure 6 is a plan view of the switch unit shown in Figures 4 and 5.

Figure 7 is a cross sectional plan view the section being taken along line 7-7 of Figure 4.

Figure 8 is an elevational view of one of the solenoids which regulate the application of the drive wheel and of the brake.

Figure 9 is a sectional elevational view of said solenoid, the section being taken along line 9-9 of Figure 8.

Figure 10 is a perspective view of the locking mechanism holding the driving unit on the chair.

Figure 11 is a sectional elevational view of one of the drive rollers.

Figure 12 is a diagram of the electric connections.

Figure 13 is a partly sectional view of a clutch coupling to be used in connection with a modification of the braking and driving unit.

Figure 14 is an elevational sectional side view of a double relay switch adapted to close one pair of contacts while opening a second pair.

Figures 15, 16 and 17 illustrate diagrammatically three different phases of the position of the driving roller and brake.

Figure 18 is a diagram showing a modified form of the master control switch or "stick."

Figure 19 illustrates a further modification of the arrangement illustrated in Figure 13.

The electrically propelled wheel chair according to the invention is based on the principle to govern all its movements by a single master control switch lever or stick. This movement, therefore, controls the angular direction as well as the forward or backward movement of the chair, the starting, stopping and braking. The said master control switch lever or stick therefore forms the steering mechanism as well as the drive control and brake application mechanism.

Briefly stated, the entire control of the chair is concentrated in this switch lever and is performed by moving said lever into different directions. Additional switches are merely necessary to cut out the current altogether and to change the speed of driving, but even the latter switch

may be seated on or connected with the master control lever or stick. The same master control lever may also be used for applying the brakes and for cutting out the motor for bringing the wheel chair to a sudden stop, by moving it axially for example.

This principle of using a substantially unified control of the chair by means of a single lever instead of using a separate steering mechanism and a separate motion control mechanism, supplemented by some further controls of minor importance is applied by using separately controllable driving and braking devices for each propelling wheel, which permit driving of one wheel while the other is under the influence of a brake so that the steering may be obtained by producing differences of speed between the wheels resulting in a turning or pivoting of the chair around the wheel which is held back while the other is driven.

Referring now to the embodiment shown in the drawing it will be seen that Figure 1 shows a standard wheel chair construction for invalids which need not be described in detail and which includes a frame 20 made of welded metal tubes carrying a seat 21, a back 22, a foot rest 23 supported by main driving wheels 26 provided with hand rims 30 and rotatably mounted on an axle pin 29. Moreover the chair is provided with front rollers 28 mounted in a sheaf 33 turning around an axle pin 27. The vertical tubes or struts 32 which carry the axle pin 29 end in push bars or handles 24 while the vertical struts 31 are bent horizontally and form a support for the arm rests 36 covering the said horizontal portions.

The lower portion of the framework consists of a pair of horizontal tubes 25 which may or may not be joined by a transverse brace.

As above stated the wheel chair which has thus far described is a standard construction to which the invention may be fitted, but which is not changed or modified when the invention is applied. It seems therefore unnecessary to describe it further.

The driving mechanism for this standard wheel chair comprises a frame 40 made of a band or angle iron and which comprises two parallel sections 41 joined by a transverse section 42 at the end and by further transverse members 44. The two parallel sections 41 carry angles or a band iron with outwardly bent flanges or ends 43 at each side, said ends or flanges projecting outwardly at right angle to the section 41 of frame 40.

The flanges or bent ends 43 are provided with circular cuts 45 fitting the tubular frame members 25 of the wheel chair frame and when said flanges have been secured on the tubular members it will be clear that the entire frame 40 is firmly held on the chair with the driving members of the drive mechanism in engagement with the wheels of the chair as described below.

To secure it in its position the mechanism shown in Figures 3 and 10 is used. It consists of a locking tongue 46 with a bent end 47 adapted to be drawn against the vertical strut or tube 32 by a small lock lever 48 to which it is linked eccentrically at 49. The lever 48 is pivoted at 50 to a Z-shaped bracket 51 fixed to the band iron section 41 near the flange 43. The eccentric link or lock lever 48 is provided with a thumb piece 52 at its end and when turned this thumb piece pulls the end of the locking tongue 46 against the vertical strut 32 securing a firm holding. The

lock lever 48 finally abuts against the projecting flange 43 and by virtue of the eccentricity of the pivot link 49 the lock lever, once it has been turned downwardly, will remain locked in its position without being capable to turn back. The two lock mechanisms on both sides of the frame 40 therefore lock the said frame securely to the frame 29 of the wheel chair, thereby securely to the frame 28 of the wheel chair, thereby securing automatic engagement of the driving members of the drive mechanism with the wheels as described below.

The frame 40 supports practically the entire driving mechanism. This mechanism consists of an electromotor 60 held by suitable longitudinal and transverse struts and shields which drives a shaft 61 carrying a pulley 62. The motor may be provided with a suitable gear box if necessary to bring the speed of the pulley to the desired value at the maximal or normal motor speed. This pulley drives a further drive pulley 65 by means of a belt, preferably a rubber belt 66. The pulley 65 is keyed to a shaft 70 which is held in bearings 73 supported by arms 68 which are fixed on the frame 40 by means of bolts 69 permitting a certain amount of angular movement. The bolts 69 may be secured by nuts 71 which provide the required amount of friction so that a pivotal movement around bolts 71 can only take place under a somewhat heavy load.

Each end of the shaft 70 also carries a U-shaped frame 75 and the driving roller 80, the latter being keyed to the shaft by means of the set screw 76.

The driving roller 80 has a V-shaped groove 77, the profile or cross section of which shows a flat portion flanked by inclined walls. This groove therefore may engage the standard driving wheel of a wheel chair and establish frictional contact with the peripheral portion of the tire on the said wheel. The frictional contact is automatically established when the frame 40 is in its place and is locked on the tubes 25 of the wheel chair.

The frame 75 carries moreover a brake roller 78, the application of which against the tire produces a strong braking action by friction which arrests the driving wheel. This brake roller may be held on the frame by means of the bolt 79.

Each frame 75 is connected with a lever arm 82 pivoted at 94 to the core 91 of a solenoid 90. The connection of the lever arm 82 with the frame 75 is made at one end thereof, such as the end carrying the bolt 79 and said connection may be made by means of the nut holding the bolt in place. A brace or strut 83 is moreover used to connect an intermediate point 84 on the lever 82 with the other end of the frame, where the brace or strut 83 is fixed by means of a threaded bolt 85. A movement of the lever produced by the solenoid has therefore the tendency to push the lower portion of the frame outwardly, and away from the solenoid while the said movement of the lever 82 has also the tendency to move the upper point 79 of the frame inwardly towards the solenoid 90.

The solenoids 90 are provided with coils 93 and in the example shown each coil surrounds a sleeve 95 passing through the center of the coil which serves as a holder for the solenoid. The sleeve 95 for this purpose is closed at its lower end by a plug 97 and a bolt 96 passes through it and said plug, carrying the solenoid structure. The bolt 96 is fixed to the band iron 41 of the frame 40.

The plug 97 also serves as an abutment for the

spring 98 inserted into the sleeve and pressing against the core 91. The sleeve in its upper portion is provided with a slot 99 permitting the passage of the bar 82.

The frame 40 moreover carries a storage battery 100, which may be held on transverse bars (not shown) by means of the two posts 101 with bent ends 102 through which screw bolts 103 pass which are applied against the upper edge of the battery. The battery is provided with a charging unit, so that it can be recharged when exhausted by plugging in a wall plug 110 into the outlet of an A. C. network. This unit which is also indicated in the diagram Figure 12 comprises the transformer 112 and the rectifier set 114.

The regulation of the motor speed is obtained by means of a resistance 116 cooperating with a relay switch 118 arranged in parallel thereto. When the relay switch is energized the resistance is short circuited and the motor runs at maximal speed. When the relay switch is deenergized the resistance is in the supply circuit of the motor 60 and thereby the speed of the motor is reduced.

The control of the direction of rotation of the motor is effected by a number of relay switches 120, 121, 122, 123 each controlling a set of contacts. These relay switches may form a single constructional unit as shown in Figure 2 mounted on a transverse bar 44. As the relay switches are only operated alternatively as will be explained below they may be replaced by twin solenoid switches 130 such as shown in Figure 14 with two solenoid coils 124, 125 acting on a common movable core 126 which carries a contact bar 127 with contacts 128, 129 which may cooperate with fixed contacts 131, 132, 133, 134. The core 126 may be held in a neutral position by springs 135 held within a sleeve of non-magnetic material within which the core is sliding.

The entire electric driving mechanism mounted on the frame 40 may be concealed and protected by a cover 140 such as shown in Figures 1 and 3. Merely the shaft 70, drive wheel 65 and the associated parts such as the frames 75 and rollers 80 are therefore outside the cover and are visible and accessible so that the electrical part of the unit is fully protected against accidental damage.

The control of the wheel chair by its occupant is exercised as has been explained by a single master control switch lever 150 which forms simultaneously the steering mechanism, the reversing mechanism and the stop and start mechanism, as far as intermittent stopping and starting is concerned. The master control switch generally indicated at 145 is preferably mounted on the arm supporting rail 36 by means of a U-shaped bracket 136 carrying a clamping screw 137. The said clamping screw is provided with a clamping disk 138 which may be pressed against the arm supporting rail.

The master control switch 145 comprises a cover plate 160 of insulating material and a frame consisting of a bent plate 139, with an upper horizontal plate portion 141 attached to the cover plate 160 by rivets 161 and resting on the arm support rail 36 and a lower horizontal portion 142, the two horizontal portions being joined by a vertical member which carries the supporting bracket 136.

In the lower horizontal plate portion 142 an insulating bushing 143 is inserted and through this bushing a screw bolt 144 is threaded which

also forms a terminal post for connecting it with a current carrying wire and which is fixed by a number of nuts. Said screw bolt carries an elastic rod or spring member 146 movable in all directions against some elastic tension. The spring member in its turn carries the switch arm 159 which comprises a cylindrical metallic portion 151 surmounted by a handle 152 of insulating material on its top.

The cylindrical member 151 passes through an outer cylindrical casing 154 which may be of insulating material and in the interior of which four contact leaf springs 155, 156, 157, 158 are arranged, two contact leaf springs forming a pair facing each other and the two pairs being arranged at right angle to each other. The leaf springs thus are disposed so as to form part of a square surrounding the cylindrical metal cylinder 151. The leaf springs are preferably disposed across the four main directions of movement as viewed from the position of the occupant of the chair. Each leaf spring is connected with a terminal post 159 with which an electric connection may be made so that each leaf spring is connected with a separate circuit or part of a circuit.

It will therefore be clear that when the master control switch lever 150 is moved by the occupant of the chair in a forward direction the metallic switch portion 151 will make contact with leaf spring 155 located in front and when the handle is moved to the right, contact will be made with spring 156 provided the switch is mounted on the right arm support rail, and is operated with the right hand of the occupant.

The switch may also be moved in a diagonal or under an angle to the forward and backward direction and in this case the member 151 may make contact for instance with both contact springs 155 and 156.

The cover plate 160 also carries two switches 164, 165 which may be of the usual type and are shown as tumbler switches. One of said switches controls the admission of current to the drive mechanism. The other switch controls the speed. Their function in detail will be seen from the diagram Figure 12.

The diagram of connections shown in Figure 12 explains itself as the reference numerals are identical with those above explained. It may only be added that the reversal of the motion of the chair is obtained by reversing the motor 60; the latter operation is performed by reversing the current direction in the field (or in the armature) winding. The ground connections indicated in the diagram are return connections obtained by means of the chair frame.

The operation of the arm chair by means of the single master control lever is the following.

The switch 165 which cuts out the entire current supply must first be closed in order to put the chair into condition for action. When this has been done the master control lever 150 is connected with the battery 160 by conductor 166, but no movement will occur as long as the master control lever is not moved. Let it be assumed now that straight forward movement is intended; then the occupant of the chair moves the master control lever 150 straight forward making contact with contact spring 155. This closes a circuit through conductor 166, master control lever 150, contact spring 155, conductor 167 and relay switches 120 and 121. Relay switches 120 and 121 close their contacts and an energizing circuit for the motor 60 is thereby

closed. If the occupant leaves switch 164 open because he wants to drive the wheel chair at low speed this circuit may be traced from battery 160, conductor 168, resistance 116, conductors 168 and 170 through closed contacts of relay switch 120, through field winding 171 of motor 60, closed contacts of switch relay 121 through armature 172 to ground. The motor 60 starts to turn in a forward direction, with the current flowing through the field winding in the direction of the arrow.

Should the occupant have desired a backward movement he would have moved the master control lever backward contacting spring 157 and 15 closing a circuit through relay switches 122 and 123, through conductor 172. The current through the motor, instead of passing conductor 170, will then flow through conductor 174 and through closed contacts of switch 123 and conductor 176 through the armature of motor 60 to ground. The current through field winding 171 being reversed the motor 60 will rotate in the opposite direction.

Rotation of the motor drives shaft 61, pulley 25 62, pulley 65 (Figure 2) and shaft 70. The rotation of shaft 70 rotates the rollers 80 which are in frictional contact with the tires of the wheels 26 and the wheels will thereby be driven in the desired direction.

30 Let it be assumed now that the occupant of the chair while going forward wants to turn to his right. He then moves the master control lever diagonally so that said lever touches both contact springs 155 and 156. Thereby two circuits are closed.

35 One of them being the motor circuit which has already been described. The second circuit is the circuit 177 of the right solenoid 90 marked 90a in Figure 12. This solenoid will attract its core and will lower its lever 82.

40 Thereby as seen in Figures 15, 16, 17, the frame 75 with the grooved drive roller 80 and the brake roller 78 is subjected to a force which pushes the lower part of the frame away from the wheel, while the upper part is drawn towards the wheel. The movement thus imparted is only slight but it results in pressing the brake roller against the tire of the wheel while the roller 80 is moved out of engagement. The right wheel is therefore subjected to a braking action while the left wheel moves ahead and the chair is thus turned to the right.

45 The movement of the frame 75 is based on the resiliency of the shaft 70 and shaft bearing arm 68 and on the slackness of the belt 66, but experience has shown that the minute movements which are necessary are absorbed by the resiliency of the members without any difficulty.

50 It has been mentioned that switch 164 serves the purpose of changing the motor speed, so as to be able to drive the wheel chair either at a low or at a higher speed. This result is obtained by means of relay switch 118 which permits to short circuit resistance 116. It will be clear that the closure of switch 164 located near the master control lever 150 energizes relay switch 118 over conductor 168 and both switches 165 and 164 and the energization of the relay switch in its turn closes the circuit branch 169, located in parallel to resistance 116. Therefore the resistance is no longer active and the amperage of the current flowing through motor 60 is increased, resulting in a higher speed of rotation.

55 A modification of the above described arrangement is illustrated in Figure 13. According to this modification the shaft 70 carry-

ing the pulley 65 is held in bearings 73 and is coupled with the shaft sections 180, 181 carrying the drive rollers 80 by means of magnetic couplings 182, 183 which also operate the braking means. The couplings 182, 183 comprise disks 184, keyed to the shaft 70 and further ferromagnetic armature disks 185 frictionally or otherwise engaging disks 184 and seated on shaft sections 180 and 181 respectively. Disks 185 are keyed to the shaft sections but are displaceable. They are pressed towards disks 184 by means of disk or cup shaped springs 187, held by a collar 186 fixed on the shaft sections 180, 181.

At the rear of disks 185 annular brake linings 188 are provided, cooperating with similar annular linings 189 on the annular front ends of electromagnet housings 192 which, preferably are fixedly held on brackets 191 fixed to one of the transverse struts of the frame.

The magnet housings 192 have the shape of cylindrical cups arranged coaxially with the shaft sections 180, 181. They contain the coils 190, 190a which are also arranged coaxially with the shaft sections 70, 180, 181.

It will be obvious that the ferromagnetic disks 185 form the armature of the electromagnet and are attracted by the magnetic field set up in the housing and passing through the disks towards the former. As long as the electromagnets 190, 190a are deenergized the springs 187 press the armature disks 185 towards the coupling disks 184 of shaft 70 and maintain a coupling between the shaft section 180 or 181 and shaft 70. When the electromagnet 190 or 190a is energized the armature disk 185 moves toward the electromagnet housing 192 and is disengaged from frictional or other contact with disk 184. Simultaneously the brake lining 188 is pressed towards lining 189 on the front end of the electromagnet housing and the shaft section (180 or 181) is effectively braked, thereby also braking the main drive wheel engaged by the roller on said shaft section.

It will be clear that the electromagnets 190, 190a may be connected in the same way in which the solenoid coils 90, 90a are connected, as they perform the same function of disengaging the driving roller from the driving shaft and of braking the shaft in engagement with the driving wheel.

As indicated in Figure 19 the motor 60 may in this case be coaxial with shaft 70 and may directly drive said shaft. It may be placed on brackets (not shown) held on the frame.

Figure 18 shows a modification of the master control switch diagrammatically. It may be desirable to provide means for stopping the wheel chair suddenly by the application of brakes on both wheels, which action should be accompanied by a breaking of the motor circuit without any additional manipulation. As seen from Figure 18 the master control lever 150 in this case is mounted on a collar 195 which is spring pressed, so that it may be moved downwardly against the action of spring 196.

The lever is provided with two contacts 197, 198 each cooperating with a set of stationary contacts 199, 200, 201. Contacts 200 are in a circuit branch supplying the motor with current and are closed in the normal position of the lever. Contacts 199 and 201 are connected with the two solenoids 90a, 90b, respectively. Upon depression of the master control lever both solenoids 90a and 90b are energized so that the brake rollers are applied on both wheels, while

simultaneously the supply circuit for the motor is interrupted.

The main advantages of the wheel chair reside in its extreme maneuverability by means of slight movements of the hand which may effect control while the arm rests on the arm support rail. No additional finger or foot control is necessary and no moving of the arms, such as usually required to steer the chair need be used. All the maneuvering may be done by moving the master control lever or stick slightly. In spite of this type of control centered in a single control lever or stick simultaneous double operations such as applying brakes while breaking the motor circuit, applying the brakes on one side while driving in any direction on the other side may be performed.

Moreover it will be noted that the driving unit is self contained and may be removed from one chair and fixed to another chair by an extremely simple manipulation without any pre-adjustment or the like. Moreover as stated the unit is equipped with all recharging means for the storage battery and may therefore be recharged by unskilled persons and in many cases by the person using the chair.

It will be clear from the description of the details that many changes may be made which will not affect the essence of the invention.

Having described the invention, what is claimed as new is:

1. An electrically propelled wheel chair with two main driving wheels, comprising a frictional drive roller for each main driving wheel, a braking means for each wheel, electromagnetic means for bringing said frictional drive roller and said braking means alternatively into and out of operative connection with each wheel for steering and braking purposes, an electromotor provided with means for driving said frictional driving roller, operative circuits for said electromagnetic means and for said electromotor and a master control switch with a manually controlled master control lever, carrying a movable contact means, said switch being further provided with a number of fixed control contacts adapted to be brought into operative contact with the movable contact means upon movement of the master control lever for selectively closing the operative circuits of the electromotor and of the electromagnetic means.

2. An electrically propelled wheel chair with two main driving wheels, comprising an electromotor, operative circuits for the same, a shaft driven by said electromotor, disengageable friction drive rollers on said shaft each drive roller being normally in frictional engagement with one of said main driving wheels, brake members for each main driving wheel carried by said shaft, means for withdrawing each of said drive rollers from normal frictional engagement with the driving wheel with which it is engaged and for bringing said brake member simultaneously into engagement with the main driving wheel from which the drive roller was disengaged, a solenoid for operating said means, an operative circuit for the solenoid, a master control switch on said chair provided with fixed contacts, controlling the operative circuits of the electromotor and the operative circuits of each of the solenoids, said contacts being grouped around a center, and a master control switch lever arranged in the center of the group of fixed contacts and provided with a movable contact adapted to be moved in all directions and make con-

tact alternatively with selected fixed contacts controlling propelling and steering of the wheel chair by the alternative and simultaneous energization of selected circuits.

3. An electrically propelled wheel chair with two main driving wheels, comprising an electromotor, operative circuits for the same, a shaft driven by said electromotor, disengageable friction drive rollers on said shaft, each normally in frictional engagement with one of said main driving wheels, frame members carried by said shaft, said frame members carrying brake members, each adapted to be applied against one of the main drive wheels, a frame rocking member for each frame member attached to the ends of each of the said frame members, a solenoid for operating each of said frame rocking members, an operative circuit for each of said solenoids, a master control switch on said chair provided with fixed contacts, controlling the operative circuits of the electromotor and the operative circuits of each of the solenoids, said contacts being grouped around a center and a master control switch lever arranged in the center of the group of fixed contacts and provided with a central movable contact adapted to be moved in all directions for making contact with said fixed contacts controlling propelling and steering by the alternative and simultaneous energization of selected circuits.

4. An electrically propelled wheel chair with a frame and two main driving wheels comprising a storage battery, an electromotor, a shaft driven by said electromotor, frictional driving rollers on said shaft, each driving roller normally engaging one of the main driving wheels, a brake roller carried by said shaft near each of said driving rollers, electromagnetic means for applying each brake roller separately and for disengaging each of said driving rollers from frictional engagement with the main driving wheel, relay switches controlling the direction of current flow from the storage battery to the electromotor, a frame for supporting the storage battery, an electromotor shaft, driving rollers, brake rollers and relay switches, and locking means for locking said frame to the wheel chair frame thereby bringing the driving rollers into frictional engagement with the main driving wheels of the arm chair.

5. An electrically propelled wheel chair with a frame and two main driving wheels comprising a storage battery, an electromotor, a shaft driven by said electromotor, frictional driving rollers on said shaft, each driving roller normally engaging one of the main driving wheels, a frame surrounding each roller on said shaft, a brake roller on said frame, means for producing a rocking movement of said frame for simultaneously applying the brake roller and for disengaging the frictional engagement between the drive roller and the main driving wheel of the wheel chair, electromagnetic means for operating the above named means producing the rocking movement of the frame, relay switches controlling the direction of current flow from the storage battery to the electromotor, a frame for supporting the storage battery, electromotor, shaft, driving rollers, brake rollers and relay switches, locking means for locking said frame to the wheel chair frame, thereby producing frictional engagement between the main drive wheels of the chair and the driving rollers on the shaft, a master control switch provided with fixed contacts each connected with one of the said relay switches and with further fixed contacts each controlling one

of the said electromagnetic means, and a single, hand-operated master control lever movable in all directions, carrying a movable contact connected with the storage battery and, when moved toward the fixed contacts, adapted to close the operative circuits either of one of the said relay switches or of one of the said electromagnetic means or, alternatively, to close the operative circuits of one of the relay switches and of one of the electromagnetic means simultaneously.

5 6. An electrically propelled wheel chair with a frame and two main driving wheels comprising a storage battery, an electromotor, a shaft driven by said electromotor, frictional driving rollers on said shaft, each driving roller normally engaging one of the main driving wheels, a frame surrounding each roller on said shaft, a brake roller on said frame, means for producing a rocking movement of said frame for simultaneously applying the brake roller and for disengaging the frictional engagement between the drive roller and the main driving wheel of the wheel chair, electromagnetic means for operating the above named means for producing a rocking movement 15 of the frame, relay switches controlling the direction of current flow from the storage battery to the electromotor, operative circuits for each of said relay switches and for each of said electromagnetic means, a master control switch provided with fixed contacts each connected with one of the said relay switches and with further fixed contacts, each controlling one of the said electromagnetic means, a single hand-operated master control lever movable in all directions 20 carrying a movable contact connected with the storage battery, and, when moved towards the fixed contacts, adapted to close the operative circuits either of one of the said relay switches or of one of the said electromagnetic means, or 25 alternatively to close the operative circuits of one of the relay switches and of one of the electromagnetic means simultaneously provided with fixed contacts controlling the said relay switches and with further fixed contacts controlling the 30 said electromagnetic means and further provided with a single hand operated master control lever carrying a movable contact manually movable in all directions and adapted to close the operative circuits of each of the said relay switches 35 and of each of said electromagnetic means singly or to close simultaneously a control contact of the relay switches and a control contact of one of the electromagnetic devices, a further relay switch controlling the amperage of the current 40 flowing through the operative circuit of the motor and a further switch near the master control switch for controlling said last named relay switch.

7. An electrically propelled wheel chair with a 45 frame and two main driving wheels comprising a storage battery, an electromotor, a shaft driven by said electromotor, frictional driving rollers on said shaft, each driving roller normally engaging one of the main driving wheels, a frame surrounding each roller on said shaft, a brake roller on said frame, means for producing a rocking movement of said frame for simultaneously applying the brake roller and for disengaging the frictional engagement between the drive roller and the main driving wheel of the wheel chair, electromagnetic means for operating the above 50 named means for producing a rocking movement of the frame, relay switches controlling the direction of current flow from the storage battery to the electromotor, operative circuits for each 55 to the electromotor, operative circuits for each

of said relay switches and each of said electromagnetic means, a single master control switch provided with at least two fixed contacts facing each other each connected with one of the relay switches, controlling the direction of current flow to and thereby the direction of rotation of the electromotor and the direction of movement of the main driving wheels of the chair, two further fixed contacts facing each other and arranged at right angle to the first named two contacts, each of said further fixed contacts being connected with one of the electromagnetic means applying the brake and disengaging the driving roller from the main driving wheel, all said fixed contacts being arranged around a center, a single master control lever arranged substantially in the center between the fixed contacts and provided with a central movable contact connected with the storage battery, said central movable contact being out of contact with all the fixed contacts in the position of rest of the master control lever and being adapted to close either one of the operative circuits of the relay switches for a selected direction of current or a selected circuit of one of said electromagnetic means or alternatively closing simultaneously the operative circuits of one of the relay switches and of a selected one of the electromagnetic means, elastic means for holding said master control lever in its position of rest, said means being yieldable in all directions under manual pressure, the direction of movement of the wheel chair being determined by the fixed contact or contacts to which the master control lever is moved for producing the closure of one or more of the aforesaid operative circuits.

8. An electrically propelled wheel chair with a frame and two main driving wheels comprising a storage battery, an electromotor, a shaft driven by said electromotor, frictional driving rollers on said shaft, each driving roller normally engaging one of the main driving wheels, a frame surrounding each roller on said shaft, a brake roller on said frame, means for producing a rocking movement of said frame for simultaneously applying the brake roller and for disengaging the frictional engagement between the drive roller and the main driving wheel of the wheel chair, electromagnetic means for operating the above-named means for producing a rocking movement of the frame, relay switches controlling the direction of current flow from the storage battery to the electromotor, operative circuits for each of said relay switches and each of said electromagnetic means, a single master control switch for controlling the said operative circuit, said master control switch comprising at least two fixed contacts facing each other connected with relay switches, controlling the direction of rotation of the electromotor and thereby the direction of movement of the main driving wheels of the chair, two further fixed contacts facing each other and arranged at right angle to the first named two contacts, each of said further fixed contacts being connected with one of the electromagnetic means applying the brake and disengaging the driving roller from the main driving wheel, all said fixed contacts being arranged around a center, a single master control lever arranged substantially in the center between the fixed contacts and provided with a central movable contact connected with the storage battery, said central contact being movable towards the fixed contacts and out of contact with all the fixed contacts in the position of rest of the master

control lever and being adapted to close either one of the operative circuits of the relay switches for a selected direction of current or a selected circuit of one of said electromagnetic means or, alternatively, closing simultaneously the operative circuits of one of the relay switches and of a selected one of the electromagnetic means, elastic means for holding said master control lever in its position of rest, the means being yieldable in all directions under manual pressure, said direction of movement of the wheel chair being determined by the fixed contact or contacts towards which the master control lever is moved for producing the closure of one or more of the aforesaid operative circuits, and further contacts on said master control lever closing the contacts of all electromagnetic means simultaneously for producing a braking action on both main driving wheels.

20 9. In an electrically propelled wheel chair as claimed in claim 8, means for interrupting the current supply to the electromotor upon simultaneous closure of the contacts of both operative circuits of the electromagnetic means.

25 10. An electrically propelled wheel chair with two main driving wheels, comprising an electromotor, operative circuits for the same, a drive shaft driven by said electromotor, a friction drive roller for each of said main driving wheels normally in frictional engagement with the same, means for controlling the transmission of power from said shaft to each of the drive rollers in engagement with the main driving wheels, a brake mechanism for each main driving wheel, means for controlling both said power transmission controlling means and said brake mechanism for each main driving wheel and for making them alternatively operative, including electromagnetic coils, operative circuits for the electromotor and for each of said coils, and a single master control switch provided with fixed contacts connected with the operative circuits of the electromotor and the operative circuits of the coils respectively and further provided with a master control lever carrying a central contact movable in all directions towards the fixed contacts, said movable contact being thus adapted to control and to close selectively the operative circuits of the electromotor and of the electromagnetic coils, respectively.

50 11. An electrically propelled wheel chair with two main driving wheels, comprising an electromotor, operative circuits for the same, a drive shaft driven by said electromotor, a friction drive roller for each of said main driving wheels normally in frictional engagement with the same, means for controlling the transmission of power from said shaft to said friction driving roller, a brake mechanism for each main driving wheels, means for controlling both said controlling means and said brake mechanism and for making them alternatively operative, including electromagnetic coils, operative circuits for the electromotor and for each of said coils, and a single master control switch provided with fixed contacts connected with the operative circuits of the electromotor and the operative circuits of the coils respectively, and further provided with a master control lever carrying a central contact movable in all directions towards the fixed contacts, said movable contact being thus adapted to control and to close selectively the operative circuits of the electromotor and of the electromagnetic coils, respectively.

75 12. An electrically propelled wheel chair with

two main driving wheels, comprising an electro-motor, operative circuits for the same, a drive shaft driven by said electromotor, a friction drive roller for each of said main driving wheels normally in frictional engagement with the same, a combined electromagnetic coupling and brake mechanism between said friction drive rollers and said drive shaft, said coupling including a coupling member and a brake member, an operative circuit for each of said combined electromagnetic coupling and brake mechanisms and a single master control switch provided with fixed contacts connected with the operative circuits of the electromagnetic coupling and brake mechanism and further provided with a master control lever carrying a central contact movable in all directions towards the fixed contact, said movable contact being thus adapted to control and to close selectively the operative circuits of the electromotor and of the respective electromagnetic coupling and brake mechanisms.

13. An electrically propelled wheel chair with two main driving wheels, comprising an electro-motor, operative circuits for the same, a drive shaft driven by said electromotor, a friction drive roller for each of said main driving wheels normally in frictional engagement with the same, a shaft section for each frictional driving roller, a combined electromagnetic coupling and braking mechanism between each of said shaft sections and drive shaft, said mechanism including engageable and disengageable coupling disks on

said drive shaft and shaft sections respectively normally held in engagement, electromagnetic coils for moving one of said disks out of engagement with the other, a brake lining on said movable disk, a fixed brake lining adapted to engage said brake lining on the disk upon movement of the latter under the influence of an electromagnetic coil and spring means for returning the disk into its coupling position from its braking position, operative circuits for said electromagnetic coils and a single master control switch provided with fixed contacts connected with the operative circuits of the electromotor and of the electromagnetic coils, respectively, and further provided with a master contact lever carrying a central contact movable in all directions towards the fixed contact, said movable contact being thus adapted to control and to close selectively the operative circuits of the electromotor and of the electromagnetic coils respectively.
